US00D952803S

(12) **United States Design Patent** (10) Patent No.: **US D952,803 S**
Han (45) Date of Patent: **** May 24, 2022**

(54) **UNIVERSAL DRAIN STOPPER**

(71) Applicant: **HANGZHOU FUTU E-COMMERCE TECHNOLOGY CO., LTD.**,
 Hangzhou (CN)

(72) Inventor: **Dawei Han**, Beijing (CN)

(73) Assignee: **HANGZHOU FUTU E-COMMERCE TECHNOLOGY CO., LTD.**,
 Hangzhou (CN)

(**) Term: **15 Years**

(21) Appl. No.: **29/797,300**

(22) Filed: **Jun. 30, 2021**

(51) LOC (13) Cl. **23-01**

(52) U.S. Cl.

USPC **D23/260**; D21/473; D21/603

CLAIM

The ornamental design for a universal drain stopper, as shown and described.

DESCRIPTION

FIG. 1 is a perspective view of a universal drain stopper showing my new design;
 FIG. 2 is another perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.
